CLAIM

The ornamental design for a wall mountable holder, as shown and described.

DESCRIPTION

FIG. 1 is a perspective view of a wall mountable holder showing my new design;

FIG. 2 is a front view of a holder showing my new design.

FIG. 3 is a side view of the holder, the other side being a mirror image thereof; and,

FIG. 4 is a bottom plan view thereof, the top plan view is a mirror image thereof.

The rear view forms no part of the claimed design.

The broken lines shown in FIGS. 1 and 2 are for illustrative purposes only and form no part of the claimed design.
